Patented Nov. 21, 1967

209,357

DISPLAY STAND FOR A RING OR THE LIKE

Oskar A. Semler, 1817 Bayview Ave.,
Belmont, Calif. 94002

Filed Oct. 20, 1966, Ser. No. 4,350

Term of patent 14 years

(Cl. D80—9)

FIG. 1.

FIG. 2.

FIG. 3.

FIG. 4.

FIG. 5.

I claim:

The ornamental design for a display stand for a ring or the like, as shown.
